UNITED STATES PATENT OFFICE

NICHOLAS PAPAPETROU, OF CHICAGO, ILLINOIS

DESIGN FOR AN ADVERTISING FOLDER

Application filed July 7, 1931. Serial No. 40,446. Term of patent 14 years.

To all whom it may concern:

Be it known that I, NICHOLAS PAPAPETROU, a citizen of the United States, residing at Chicago, in the county of Cook and State of Illinois, have invented a new, original, and ornamental Design for an Advertising Folder, of which the following is a specification, reference being had to the accompanying drawings, forming part thereof.

Fig. 1 is a plan view of the cover of the advertising folder; and

Fig. 2 is a plan view of the back of the advertising folder.

I claim:

The ornamental design for an advertising folder as shown.

NICHOLAS PAPAPETROU.
